UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,205,617.

Specification of Letters Patent.

Patented Nov. 21, 1916.

Application filed May 22, 1916. Serial No. 99,127.

To all whom it may concern:

Be it known that I, CHARLES L. GOODRUM, a citizen of the United States, residing at New York, in the county of New York and State of New York, have invented certain new and useful Improvements in Telephone-Exchange Systems, of which the following is a full, clear, concise, and exact description.

This invention relates to telephone exchange systems of the type wherein the subscribers' lines terminate as calling lines in passive contacts of automatic finder switches to which they are multipled, an idle one of such switches being set in motion to seek a calling subscriber's line terminals by the mere removal of the telephone receiver from its hook by such party.

It is the object of this invention to provide a system of this character wherein the average time interval between the removal of the receiver by the calling party, and the connection with his line terminals by a finder is reduced. In systems of this character, the subscribers' lines are divided into groups, multipled to a number of automatic finder switches, dependent upon the traffic.

In accordance with this invention, the lines of all the groups appear in multiples upon each finder, and each finder shaft has a number of sets of multiply-connected brushes, one for each group of lines, adapted to wipe over the multiples of its group in search of a calling line therein. Means is provided associated with the various finder shafts, so constructed and arranged that if a call comes in simultaneously from each group, each of the finder shafts can, if idle, connect with a different one of said calling lines by a secondary movement only; that is to say, means is associated with the finder brush shafts so constructed and arranged that upon the simultaneous initiation of a call in each group, brushes, each serving a different group, will be simultaneously driven over the terminals of such groups in search of the calling lines. Means is also provided whereby, if the finder allotted to a given group is busy, another finder can, by a primary or group choosing movement followed by a secondary movement, connect with multiples of a calling line in such

group; that is to say, each finder, though arranged to give preference to a certain group, is common to all the lines of all the groups.

The invention will be best understood when described with reference to the accompanying drawings, wherein—

Figure 1 is a side elevation, partially in section, showing an automatic finder switch suitable for use in the circuit arrangement of this invention; Fig. 2 is a section on line 2—2 of Fig. 1; Fig. 3 shows the finder circuit of this invention, the switch of Fig. 1 being shown diagrammatically therein; and Fig. 4 is a view showing the manner of slipping the trip fingers on the brush tripping rod to give each group a finder which can connect with any line thereof without necessitating a group choosing operation.

Referring to Fig. 1, the line terminals 1 may be multipled across the face of a panel, as shown in U. S. Patent No. 1,127,741 issued to Amos F. Dixon, Feb. 9, 1915. With each vertical row of say 500 terminals is associated a brush carrier *c*', having fixed thereto five brush holders 4, carrying sets of brushes *b*', *b*², etc., one for each section of the row, as shown in U. S. Patent 1,123,696 issued to E. B. Craft and J. N. Reynolds, Jan. 5, 1915. As shown in detail in said patent, an insulated member *b*, fixed to a lever *l*', pivoted to an arm *a* of holder 4, normally maintains its set of brushes *b*' out of operative relation to the corresponding section *g* of the row of terminals 1. A trip rod *r*' is also provided for each brush carrier *c*' and carries spring-retracted collars *d*, one for each set of brushes. Each collar has a finger *f* normally out of the line of travel of the corresponding lever *l*. A row of five terminals *t*, one for each set of brushes *b*, is provided at the top of the panel 2, over which a brush *s*' fixed to rod *r*' is adapted to wipe. At its lower end, the trip rod *r*' is provided with a ratchet *g*, adapted to be engaged by the pawl 10 of a stepping magnet 11, and to be driven upwardly until one of the fingers *f* is in position to interlock with the lever *l*, associated with the brushes *b* which have access to the desired group *g* of terminals. The trip magnet 13 is then energized, over a circuit including brush *s*',

and the terminal of the row t belonging to the group of lines containing the calling line, and through its armature 50 and a member 14 on the rod r' twists such rod to cause the finger f , individual to the set of brushes b having access to multiples of the calling group, to interlock with the lever l of such set. The remaining fingers f pass out of the vertical plane in which the remaining levers l lie, so that when the carrier c' is raised, as will be presently described, such levers l will clear such fingers. When trip rod r' is rotated, a member 15 thereon shifts a lever 16, pivoted at 17, to the right against the tension of spring 18. This results in pawl 19 being placed in operative relation to ratchet 20 of the brush carrier c' , and a pawl 10 being rendered inoperative with regard to ratchet 9. The stepping magnet 11 is now energized, and drives the brush carrier c' upwardly, and the lever l of the desired set of brushes b is drawn downwardly by the finger f engaging therewith as the carrier c' rises. This causes the insulated member 6 to be moved to the right, whereupon the brushes b' are free to move inwardly, so as to wipe over the terminals 1 in the continued movement of the carrier c' under the control of stepping magnet 11. This is fully disclosed in the patent referred to, and therefore need not be described in detail herein. When the calling line is reached, the circuit of the stepping magnet 11 is opened. The trip rod r' referred to is maintained elevated by a pawl 20, and the carrier c' by a pawl 21. These pawls are adapted to be withdrawn upon the energization of release magnet 22.

Referring to Fig. 3, each subscriber's line A is provided with the usual line and cut-off relays 25 and 24, and terminates in multiples 51, 52 of the finder shown in Fig. 1. A test terminal 53 is also provided in the finder for each line. The line and cut-off relays 27, 28 of another line in the group to which line A belongs are also shown. A relay 29 is also provided, common to the group of lines, and its function is to start a finder in search of the calling line, upon the removal of the receiver at the substation thereof. Relays 30 and 31, whose functions will be described, are also common to the group. The finder is controlled by the well-known side switch, the escape magnet of which is indicated by the numeral 32. The trip magnet 13, stepping magnet 11 and release magnet 22, are indicated diagrammatically in Fig. 3.

Referring now to Figs. 1, 2 and 3, and assuming the finder shown in Fig. 1 to be the one allotted to the group of lines to which substation A belongs, it will be noted that the brush s' at the top of the rod r' (Fig. 1) is shown in Fig. 3 normally in engagement with the first terminal t' of the

row t . This terminal t' is multiplied to the second terminal t^2 in the finder allotted to the next group, the third terminal t^3 of the finder allotted to the third group, and so on. Assume now that a call comes in from substation A, and that the finder allotted thereto is idle. The removal of the receiver at substation A energizes the line relay 25, which, in attracting its armature, closes the following circuit: free pole of battery, left winding of relay 25, outer armature and back contact of relay 24, conductor 35, armature and spring 36 of relay 25, conductor 37, armature and back contact of relay 30, relay 29 to ground. Relay 29 energizes and locks itself directly to conductor 37, independently of the armature and back contact of relay 30, and at its right armature, closes a circuit to energize a slow relay 31. Relay 31, in attracting its right armature, extends the right grounded armature of relay 29 over conductor 38, side-switch arm 1 and its first contact, conductor 54, and armature and back contact of magnet 11 to free pole of battery. A path in parallel thereto may be traced from the right grounded armature of relay 29, conductor 39, terminal t' , brush s' , arm 2 and its first contact, escape magnet 32, trip magnet 13, free pole of battery. The escape magnet 32 is adapted to act more quickly than the magnet 11, and before magnet 11 can energize, escape magnet 32 releases the side switch into position 2. The trip magnet 13 also energizes in series with magnet 32, and, in position 2, these magnets are maintained energized over a circuit including arm 2, conductor 65, arm 1, conductor 38 and the right armatures and front contacts of relays 31, 29. Magnet 13, in operating, renders inoperative the pawl 10 and renders operative the pawl 19, as described in connection with Fig. 1. In position 2, the following circuit is closed for stepping magnet 11: free pole of battery, magnet 11, its armature and back contact, arm 1 and its second contact, conductor 38, right armature and front contact of slow relay 31, conductor 49, right armature and front contact of relay 29 to ground. This magnet, by making and breaking its own circuit, elevates the carrier c' , during which movement the selected set of brushes 40, 41 and 42 are tripped, as described, and wipe over the multiples of the group containing those of the calling line. The remaining sets of brushes b on the carrier c' , during this movement, do not engage the multiples they are adapted to serve, since the members 6 of such sets maintain the brushes pressed outwardly. As the brush 42 passes over the multiples 53, cut-off relays 24 are operated in succession. When the cut-off relay 24 of the calling line is reached and attracts its armatures, the corresponding line relay 25 falls back, open-

ing the circuit of starting relay 29. Relay 29, in retracting its right armature, opens the circuit of magnet 11, thus stopping the brushes 40, 41 and 42 upon the calling line 5 multiples 51, 52 and 53. The retraction of this armature also deenergizes magnets 32 and 13, the deenergization of the former releasing the side switch into position 3.

In position 3, arm 3 maintains ground upon brush 42, thus maintaining the cut-off relay 24 energized. Side-switch arms 70 and 71 now extend the calling line through to conductors 43, 44, which may terminate in a first selector, or at an operator's position, 10 depending upon the character of the system. Side-switch arm 72, in moving into position 3, prepares a circuit for the release magnet 22 of the finder. In the finder F^2 , allotted to the next group of lines, the terminal of 15 the group to which substation A belongs appears as the second terminal t^2 from the bottom. In the next group, this terminal appears as the third terminal t^3 from the bottom and so on. The arrangement is such 20 that in the finder allotted to a given group, a call from one of the lines thereof will result in the finger f of such finder interlocking with the lever l of a set of brushes having access to multiples of such group, 25 the remaining fingers f passing out of the line of travel of the other levers l . If the finder allotted to the group to which substation A belongs is busy, the next idle 30 finder is associated with such group over side-switch arm 1 and starter wire 48. As side-switch arm 1 moves into position 3, the remaining lines of the group to which substation A belongs, and those of the other groups beyond, from which in-starter wire 35 47 leads, are associated with the next idle finder by starter wire 48. Assuming that another line in the group to which substation A belongs initiates a call, while the finder of Fig. 3, which is the one allotted to 40 such group, is busy, the relay 29 is energized as before, and applies ground to the multiples t^1 , t^2 , t^3 of the group of multiples t in the finders in which this group of lines appears, and energizes relay 31, which closes 45 the following circuit; ground, right armature and front contact of relay 29, conductors 39, 49, right armature and front contact of relay 31, conductor 38, arm 1 and its third contact, conductor 48, arm 1 and its 50 first contact of finder F^2 , conductor 54 of such finder, armature and back contact of magnet 11, free pole of battery. Magnet 11 55 interrupts its own circuit, thus elevating the trip rod r^2 of the finder F^2 . When brush s^2 60 engages grounded multiple t^2 , a circuit is closed for the escape magnet 32 of finder F^2 and trip magnet 13 of such finder in series. At that instant, the finger f on the trip rod r^2 of such finder is in position to interlock 65 with lever l of the brush set b having access

to multiples of the calling group. The energization of magnet 13 causes such finger and lever to interlock, and since in position 2 the circuit of this magnet and magnet 11 is maintained, as hereinbefore described, the 70 carrier c is elevated and the lever l is drawn downwardly, as it passes finger f , whereupon the set of brushes wipes over multiples of the group containing those of the calling line. When cut-off relay 24 of the calling 75 line is reached and operated, deenergizing relay 25, the relay 29 deenergizes, opening the circuits of magnets 11, 32 and 13, stopping the finder brushes upon the calling line terminals. Upon the disestablishment of 80 the connection, ground may be placed upon conductor 45 in any well-known manner, thus energizing the finder release magnet 22 over off-normal contact 46, which releases the finder. The release magnet in operating 85 restores the side switch in the well-known manner.

While in the diagrammatic showing (Fig. 3), the second finder F^2 is located immediately to the right of the first finder F' , in actual practice, it is preferred to arrange them as shown in Fig. 4, wherein the ninth finder from F' in point of location would be the next finder to F' with regard to the advanced starter wire; that is to say, 90 if finder F' were busy and a call is initiated in the group to which it is allotted, such call would start finder F^2 (Fig. 4) in motion, if such finder were idle. An inspection of Fig. 4 shows that the finder F' , allotted 95 to the group containing substation A, which we will assume to be the first group, has a finger f' , the lowermost one on the rod r' normally in position to interlock with the lever l' of the set of brushes b' having 100 access to multiples of this group; that the finder F^2 , allotted to the second group, has a finger f^2 , normally in position to interlock with a lever l^2 of a set of brushes b^2 having 105 access to the line group to which it is allotted, and a finger 58 adapted upon one 110 step being given the trip rod r^2 to be in position to interlock, when such rod is rotated, with the lever 59 of a set of brushes 115 60 having access to multiples of the group to which substation A belongs.

What is claimed is:—

1. In an automatic telephone exchange system wherein calling lines are divided into groups, the groups terminating in different sections of a row of terminals multiplied so as to be accessible to a number of brush carriers, the combination with a carrier for each row, driving means for said carriers, and multiply connected brushes mounted on said carriers, one for each section of terminals, of means associated with said carriers and so constructed and arranged that upon the simultaneous initiation of calls in several of said groups, 120 125 130

- brushes, each serving a different section, will be simultaneously driven over such sections by said driving means in search of the calling lines.
5. In an automatic telephone exchange system wherein calling lines are divided into groups, each of said groups terminating in a different section of a row of terminals multiplied so as to be accessible to a number of brush carriers, the combination with a carrier for each row, and multiply connected brushes mounted thereon, one for each section of terminals, said brushes being normally in inoperative relation to the sections they are adapted to serve, of means associated with said carriers and so constructed and arranged that upon the simultaneous initiation of calls in several of said groups, brushes, each serving a different section, will be rendered operative, and means for thereupon driving said carriers to cause said brushes to wipe over the corresponding sections in search of the calling lines.
6. In an automatic telephone exchange system wherein calling lines are divided into groups, said groups terminating in different sections of a row of terminals multiplied so as to be accessible to a number of brush carriers, the combination with a carrier for each row, and multiply connected brushes mounted thereon, one for each section of terminals, said brushes being normally in inoperative relation to the sections they are adapted to serve, of a trip rod associated with each carrier, each rod having a tripping device for each brush thereon, means for actuating said rod to render one of said brushes operative upon the initiation of a call, the relation of the tripping devices to the brushes on the various carriers being such that when calls come in from several of the groups simultaneously said trip rods render operative brushes serving a different section in each row, and means for driving said carriers to cause said brushes to wipe over the corresponding sections in search of the calling lines.
7. In an automatic telephone exchange system wherein calling lines are divided into groups, said groups terminating in different sections of a vertical row of terminals multiplied across the face of a panel so as to be accessible to a number of brush carriers, the combination with a carrier for each vertical row, driving means for said carriers, and multiply connected brushes mounted on said carriers, one for each section of the row, of means associated with said carriers and constructed and arranged, upon the simultaneous initiation of calls in several of said groups, to cause said carriers to be driven by said driving means over said rows with a brush serving a different section in each row wiping over the terminals of said section in search of the calling lines.
8. In an automatic telephone exchange system wherein calling lines are divided into groups, each of said groups terminating in a different section of a row of terminals multiplied so as to be accessible to a number of brush carriers, the combination with a carrier for each row, each carrier being allotted to a different line group, and multiply connected brushes mounted thereon, one for each section of terminals, each brush having a trip lever and resting at the base of the section it is adapted to serve and being normally pressed out of the line of the terminals, of a trip rod associated with each carrier, each rod having a tripping finger for each brush thereon, means for simultaneously rotating said rods upon the initiation of a call in each group, the relation of the fingers on the various trip rods being such that a finger associated with a brush serving a different section in each row is interlocked with the lever of such brush, and means for driving said carriers, during which movement said fingers cause the corresponding levers to trip the associated brushes.
9. In an automatic telephone exchange system wherein calling lines are divided into groups, each of said groups terminating in a different section of a row of terminals multiplied so as to be accessible to a number of brush carriers, the combination with a carrier for each row, and multiply connected brushes mounted thereon, one for each section of terminals, each brush having a trip lever and resting at the base of the section it is adapted to serve and being normally pressed out of the line of the terminals, of a trip rod associated with each carrier, each rod having a tripping finger for each brush thereon, a stepping magnet having pawls 10 and 19, the pawl 10 being normally operative to elevate the trip rod, and the pawl 19 being normally inoperative with relation to the carrier, a circuit for said stepping magnet closed upon the initiation of a call adapted to operate said magnet to elevate said trip rod to place a finger thereon in operative relation to the trip lever of the one of said brushes having access to multiples of the calling group, a magnet for rotating said rod, a circuit therefor closed when said rod is positioned to cause said finger to interlock with the associated lever and to render inoperative said pawl 10 and to render operative said pawl 19, and a circuit for said stepping magnet adapted to cause the same to elevate said carrier, during which movement said finger causes said lever to trip said brush to cause the same to wipe over the multiples of the calling group in search of the calling line.
10. In an automatic telephone exchange system wherein calling lines are divided into groups multiplied to groups of terminals in a number of finders, the combination with

the finders, a brush carrier for each finder, driving means therefor, said carrier having a plurality of multiply connected brushes, one for each group, of trip means associated with said carriers and so constructed and arranged that upon the simultaneous initiation of calls in several of said groups,

brushes, each serving a different group, will be simultaneously driven over such terminal groups by said driving means in search 10 of the calling lines.

In witness whereof, I hereunto subscribe my name this 20th day of May, A. D., 1916.

CHARLES L. GOODRUM.
